UNITED STATES PATENT OFFICE.

CHARLES CASPER, OF MERIDEN, CONNECTICUT.

DESIGN FOR A CLOCK-CASE.

SPECIFICATION forming part of Design No. 17,237, dated April 5, 1887.

Application filed February 16, 1887. Serial No. 297,852. Term of patent 7 years.

To all whom it may concern:

Be it known that I, CHARLES CASPER, a citizen of the United States, residing at Meriden, in the county of New Haven and State of Connecticut, have invented and produced a new and original Design for Clock-Cases; and I do declare the following to be a full, clear, and exact description of the same, reference being had to the accompanying photographic illustration, forming a part thereof, which represents my novel design in elevation.

The design consists of a clock-case representing a bottle and cork and bearing a dial.

1 denotes a panel upon the face of the representation of a bottle; 2, a raised bead surrounding the panel; 3, the sides of the representation of a bottle; 4, flat bevels extending from the outer edges of the raised bead to the sides of the bottle at an obtuse angle to the face of the panel and to the sides of the bottle. 5
denotes the top of the bottle, curved slightly,

as shown; 6, the neck; 7, the flange, and 8 the cork. At the center of the panel is a dial, 9, surrounded by a raised circular bead, 10, and between bead 10 and beads 2 at the corners 25 are raised ornamental leaves 11.

Having thus described my invention, I claim—

The design for a clock-case herein described and shown, consisting of a representation of a 3c bottle having upon its face a panel surrounded by a raised bead, a curved top, a neck, flange, and cork, a dial at the center of the panel surrounded by a raised circular bead, and ornamental leaves between the circular bead and 35 the bead surrounding the panel.

In testimony whereof I affix my signature in presence of two witnesses.

CHARLES CASPER.

Witnesses:

LOUIS CASPER,
JOHN WATSON.
